Bonnin & Escudier
Sugar Boiling App's.

N° 92,932.

Patented Jul 27, 1869

United States Patent Office.

MARTIAL BONNIN AND CHARLES ESCUDIER, OF NEW IBERIA,
LOUISIANA.

Letters Patent No. 92,932, dated July 27, 1869.

IMPROVED SUGAR-BOILING APPARATUS.

The Schedule referred to in these Letters Patent and making part of the same.

To all whom it may concern:

Be it known that we, MARTIAL BONNIN and CHARLES ESCUDIER, of New Iberia, parish of Iberia, State of Louisiana, have invented a new and useful Improvement in Sugar-Boiling Apparatus, with the view of economizing fuel and labor; and we do hereby declare that the following is a full, clear, and exact description of the construction and operation of the same, reference being had to the annexed drawings, making a part of this specification, in which—

Figure No. 1 is a longitudinal view.

Figures 2, 3, 4, 5, 6, transverse and detached sections of the same.

First, the kettles *a*, as here shown, are placed on a brick foundation, in a graduated scale and form, as shown by Fig. No. 1, so that so soon as it is desirable that the evaporated cane-juice or other product be transferred to the next in order, (they being numbered 1, 2, 3, 4,) by pressing down the lever *b* the sluice-gate *c* is opened, allowing the juice to flow freely from one to another, avoiding thus the method, now generally in use, of dipping with buckets.

Second, the two kettles on a level plane next to the smoke-stack, and named as shown, (Grand,) are the ones to receive the raw juice as it flows from the mill. They must be emptied alternately, and for that purpose a copper pipe of sufficient dimensions, as shown, letter *D*, is inserted in them, passing completely through the second kettle, and opened by similar process of sluice-gate lever, &c., letters *b*. *C*.

Third, as it is absolutely necessary, in the manufacture of sugar, to cleanse the juice, a skimming-gutter is provided to each kettle, letter *E*, in which skimmings are conveyed from the kettles, and from thence through the pipe *f* into the main skimming-gutter *g*, conveying the same to any kind of recipient fitted to the purpose.

Fourth, the kettles being full of juice, fire is started in the furnace *h*. The heat is conveyed under each kettle through the gradually-expanding flue passing under each of them, and being larger at the further extremity, (letter *K*;) its course is also marked by flying arrows;) thus, by the repeated elbows, checking

its too rapid draught, and securing the greatest amount of heat to a given surface.

Fifth, in order to enable the sugar-boiler or of other product to better govern his furnace, a damper, *l*, is adjusted at the termination of the flue, before reaching the smoke-stack, this damper working on a pivot completely out of reach of the fire, and so constructed as to open or shut the flue gradually on both sides equally, by turning the handle *m*, (see Figs. Nos. 1, 2, 3,) the damper being so constructed as to resist the heat to which it may be subjected.

Sixth, in the setting of kettles, two different plans are here submitted, figs. 5 and 6. Fig. 5 admits, by its construction exposing a much larger heating-surface, of a much more rapid evaporation of the juice, but in some cases, where the cane or other mills have but little power, fig. 6 may be better adapted. Fig. 5 is built with sloping sides, so as to obtain a side flue, letter *n*, whereas fig. 6 is so built as only to allow the bottom surface exposed to the heat.

Seventh, the kettles are so constructed that the method now in use, of lining the same with bricks, is here avoided. The kettles here shown, letter *o*, are made of same material, the whole forming a complete kettle, thus avoiding all brick lining, as now generally in use, fig. 4.

Claims.

What we claim as our invention or improvement, and desire to secure by Letters Patent, is—

1. The setting of square kettles in a graduated scale and position, as shown, with the expanding flue corresponding, for the purpose of evaporating cane-juice or other product substantially the same; also the two methods of setting the same.

2. Also, the pivot-damper, as here constructed and applied, in sugar or other evaporating-apparatus, the whole operating and being substantially the same.

MARTIAL BONNIN.
CHARLES ESCUDIER.
